UNITED STATES PATENT OFFICE

HAROLD W. SHONNARD, OF MONTCLAIR, NEW JERSEY, ASSIGNOR TO ELEVATOR SUPPLIES COMPANY, INC., A CORPORATION OF NEW JERSEY

SUSPENSION MEANS FOR ELEVATOR GATES

Application filed August 20, 1926. Serial No. 130,428.

My present invention has relation to a new and improved form of adjustable support for the well known type of elevator gate which is composed of vertical bars slidably joined by crossed pivoted slats, whereby the gate may be extended or collapsed at will.

Gates of this type are suspended by rollers attached to some of the vertical bars, (usually every fourth bar) which rollers are adapted to roll along horizontal tracks over the gate.

In order that there may be the proper uniform distribution of the weight of the gate along the full extent of the track, it is clearly necessary that the vertical distances between the rollers and their respective points of attachment to the gate should be everywhere equal.

Inasmuch as these parts are assembled at the elevator shaft and not at the factory, it has been the practice hitherto to mount each pair of supporting rollers upon an upright rod, the lower end of which is screwed into the proper vertical bar of the gate. Thus, by turning the bars, together with their rollers, one way or the other, the respective heights of the rollers above the gate may be adjusted to produce the desired uniformity in position.

This construction has a number of disadvantages. In the first place, this adjustment must, of course, be made while the rollers are off of their supporting tracks. Thus, if, after first hanging the gate, it is found that one or more rollers are not quite rightly adjusted, the whole gate must be removed from the tracks, and a new adjustment must be made, more or less by guess.

Again, in the course of use, uneven wear will make it necessary to readjust the rollers to prevent sagging and undue vibration, noise and resistance to movement. This makes it necessary to remove the whole gate again, which not only involves considerable labor, but interruption of service as well.

Another disadvantage of the old construction is found in the fact that, since the rollers must always be kept in line with the tracks, every adjustment must be accomplished by one or more half turns of the upright roller

supports. Fractions of a half turn are not permissible.

My present invention supplies an improved construction whereby all of these disadvantages are avoided. My improved gate suspending means may receive its final adjustment after the rollers are placed on the track, and the adjustments necessary to compensate for wear may be made while the rollers remain in place. Furthermore, my improved construction makes it possible to make a finer adjustment than hitherto possible, because it involves the turning of a screw to any desired extent without moving the rollers themselves.

The invention further provides an adjustable hanger capable of passing through a narrow slot and having a compact and mechanically strong construction.

My invention is illustrated in a preferred form in the accompanying drawings, wherein Figure 1 is a diagrammatic view in front elevation of a collapsing gate to which my improvement is applied, Figure 2 is a view in elevation of a single vertical gate bar showing my hanger in place on the tracks, Figure 3 is a similar view taken at right angles to Figure 2, and Figure 4 is a detail view partly in section of the turnbuckle.

As shown in Figure 1, the gate is composed of the vertical bars 10, united slidably by crossed and pivoted slats 11. Every fourth bar 10 is provided at the top with a hanger 12, shown in detail in Figures 2, 3 and 4.

In Figures 2 and 3 there is shown the vertical member 13 constituting the movable upright edge of the gate. One of the vertical bars 10 of the gate is shown in Figure 3 fastened to the member 13. The hanger comprises a pair of rollers 14, turning (preferably on ball rollers) on the ends of a bearing pintle 15 which passes through the enlarged top of a supporting pin 16. This pin 16 has a threaded bottom which fits the female threads in one end of a turnbuckle 17. The opposite end of the turnbuckle is threaded to screw into the top of the vertical bar 10, being preferably provided with a lock nut 18, by which its position may be made secure after adjustment. By providing a screw-threaded

socket in the turnbuckle 17, instead of in the supporting pin 16, the latter may be made relatively narrow and the distance between the rollers 14 and the top of the bars of the gate to which the hanger is attached may be short, and screw connections of good dimensions obtained.

10 The screw connection between the pin 16 and the turnbuckle is by a right handed thread and that of the turnbuckle with the bar 10 is left handed. Or the former may be left handed and the latter right handed, if preferred.

15 From this construction it is clear that, any turning, however small, of the turnbuckle (the rollers remaining stationary) will cause the gate member 10 to move up or down, according to the direction of the turn produced, thus producing the desired adjustment.

20 The tracks 19 preferably of fibre or the like, are shown supported by the metal member 20, and the adjustment above described may be accomplished with the rollers 14 in their normal position on these tracks, as 25 shown in Figure 2.

Various changes may be made in my construction without departing from the scope of the invention, which is not limited to the details herein shown and described.

30 What I claim is—

A hanger for elevator gates and the like comprising a supporting pin, a pintle transversely of said pin having rollers thereon adapted to ride on a track, said supporting pin having a threaded end-portion; and a turnbuckle, said turnbuckle having an enlarged portion adapted to be engaged by a turning implement, said enlarged portion having formed therein a threaded socket adapted to engage said threaded end of said supporting pin, said turnbuckle also having an exteriorly threaded portion adapted to fit a complementary threaded part on the gate, said threads on said turnbuckle being right 35 and left-hand threads, the distance between said rollers and the top of said gate being adjustable by turning of said turnbuckle.

40 In testimony whereof I have hereto affixed my signature on this 19th day of August, 50 1926.

HAROLD W. SHONNARD.
